Patented Nov. 15, 1921.

INVENTOR

WILLIAM T. WOOD,
by Arthur C Eckert ATTORNEY.

UNITED STATES PATENT OFFICE.

WILLIAM T. WOOD, OF ST. LOUIS, MISSOURI.

CONVEYER.

1,396,804.

Specification of Letters Patent.

Patented Nov. 15, 1921.

Application filed November 1, 1920. Serial No. 421,033.

To all whom it may concern:

Be it known that I, WILLIAM T. WOOD, a citizen of the United States of America, residing at 3860 Park avenue, St. Louis, State 5 of Missouri, have invented certain new and useful Improvements in Conveyers, of which the following is a specification.

The object of my invention is to produce a conveyer that is particularly adapted for use in packing houses in which hogs or other animals are dressed. A more particular object is to produce a conveyer in which the hooks holding the hogs etc. will be automatically fed or delivered to the operator 10 and move along at such a speed that the various operators can perform their respective operations consecutively and so that the hog etc. will be delivered automatically after being dressed, quartered etc. and one in 15 which the operation will be continuous *i. e.*, to say in which the hooks that support the hogs will be delivered to the point of beginning after the dressed hogs or parts of hogs have been removed. The conveyer is 20 built as an endless conveyer.

With the above purposes in view, my invention consists in certain novel features of construction and arrangements of parts, as will be hereinafter more fully described, 25 pointed out in the claims and illustrated in the accompanying drawings in which—

Figure 1 is a front elevation of a portion of an endless track with my device attached.

Fig. 2 is a plan view of a portion of an 30 endless track showing my device with the driving chain omitted.

Fig. 3 is a perspective view of the chain tripping element of my device and

Fig. 4 is a perspective of the feeding device of my invention.

Numeral 5 indicates a track supported by hangers 6 by means of bolts 7. The hangers 6 are supported by the roof or ceiling by means of the bolts 8.

Numeral 9 indicates a roller which is secured on an axle 10 in rotative engagement. The axle 10 is secured in the strap 11 and the roller 9 is mounted on the track 5 so that the roller may roll on the track and 45 the strap will be suspended. To the strap 11, by means of the bolt 12 are suspended vertically the hooks 13. The structure thus far described is of a conventional type. The track 5 is made to incline upward at its

50 hook receiving or right end.

Numeral 14 indicates a sprocket chain

having the projections 15 secured thereto at regular intervals as shown in Fig. 1. This sprocket chain is endless and traverses sprocket wheels at both ends (not shown.) 60 This sprocket chain is the driving element and moves from right to left in Fig. 1. When the projection 15 engages the strap 11, and moves as indicated, it pushes the roller 9, the strap 11 and the hooks 13 to the 65 left. The hogs or other animals to be dressed are secured to the hooks 13 and are delivered to the track of Fig. 1 from the right. Without my automatic feeding device the roller 9 would roll down the incline 70 of track 5 to the left until it came to the operative range of the sprocket chain 14, and when the projection 15 engaged the strap 11, the roller, strap and hooks would be moved to the extreme left of Fig. 1. This 75 would not be proper because the hooks would not be delivered in the proper consecutive time interval. The operators on the hogs stand between the two left hangers 6, and under the hook delivering mechanism, 80 each operator performing one operation while the hog etc. is moving toward the left. The hog must be positively and constantly moved toward the left without the assistance of the operator and at such a speed 85 to permit each operator to perform his task before the hog is moved to the position of the following operator, and the hogs must be automatically fed to the operators from the right. My device for accomplishing 90 this result is the following.

Numeral 16 indicates a bracket which is secured to the side of the track 5 by means of the bolts 17, which bracket supports the hook feeding device which consists of a 95 frame 18 which is firmly secured to the bracket 16 as best shown in Fig. 4. This frame consists of the horizontal arm 19, and the vertical guide 20, which guide has its upper end forked as shown in Fig. 4. Numeral 21 designates a movable arm which is rotatively secured to the bracket 16 by means of the bolt 22. This movable arm is composed of a vertical portion 23 and a horizontal portion 24. At the external end 100 of the horizontal portion 24 and at right angles thereto is firmly secured the arm 25, which is best shown in Fig. 4. The horizontal portion 24 is so positioned that in its horizontal position, it rests in the fork of 105 the vertical guide 20. A coiled spring 26 is secured to the horizontal arm 19 and the

horizontal portion 24, of the movable arm 21 so as to normally hold them in the position shown in Fig. 4. To the movable arm 21 is secured the eye 27 as shown in Fig. 4. It will be seen that when the eye 27 is pulled to the left the arm 25 will be raised.

Numeral 28 indicates a second bracket, best shown in Fig. 3 which is secured to the side of the track 5 by means of the bolts 29. 10 The bracket 28, has formed integral therewith a vertical element 30 on which is positioned the plate 31. Numeral 32 indicates a tripping finger which is rotatively secured on the plate 31 by means of the bolt 33 as 15 best shown in Fig. 3. Numeral 34 indicates an eye which is secured to the external end of the tripping finger 32. Numeral 35 indicates a rod having eyes at both ends, one of which is rotatively secured to the eye 27 and 20 the other to the eye 34. The end of the tripping finger 32 is positioned in the line of travel of the projections 15 and the arm 25 in its normal position is in the line of travel of the upper end of the straps 11. Numeral 36 indicates a stopper secured in the plate 31, to serve as a movement limiting means 25 for the tripping finger 32. The operation of my device is as follows:

The projection 15 in its travel to the left 30 engages the end of the tripping finger 32 and rotates it on the bolt 33 to the left, thereby permitting the projection 15 to move unobstructed to the left. The rotation of the tripping finger pulls the rod 35 to the left, 35 thereby rotating the movable arm 21 on its bolt in an anti-clockwise direction, thereby extending the spring 26 and raising the arm 25, thereby removing the obstruction in the path of the next roller and hook that is 40 to be fed into the operative range of the track 5. The roller and hook thereupon roll down the track to the proper position, and the arm 25 is again pulled to its normal posi-

tion by the spring 26, thereby preventing the following roller and hook from rolling 45 down the track 5. It will be seen that the distance between the projections 15 and the speed of the sprocket chain 14 will determine the intervals at which the rollers will be fed to an operative position. 50

What I claim and mean to secure by Letters Patent is—

1. In combination with a track, rollers mounted on said track in rolling engagement, straps secured to said rollers in rotative engagement, hooks secured to said straps, an endless driving chain having projections thereon, a load delivering device consisting of a movable obstruction in the path of said rollers on said track and means 55 for selectively moving said obstruction in and out of the path of said rollers, a tripping finger, operatively connected to said load delivery device, and means secured to said chain for contacting said tripping finger 60 at regular intervals.

2. In combination with a track, rollers mounted on said track in rolling engagement, said track being inclined in one portion thereof, straps secured to said rollers in 70 rotative engagement, hooks secured to said straps, an endless driving chain having projections thereon, a load delivering device consisting of a movable obstruction in the path of said rollers on said track, and means 75 for selectively moving said obstruction in and out of the path of said rollers, a tripping finger operatively connected to said delivering device and means secured to said chain for contacting said tripping finger at 80 regular intervals said tripping finger being normally positioned in the path of said track rollers.

In testimony whereof I affix my signature.

WILLIAM T. WOOD.
